J. F. MARTIN,
CANDLE HOLDER.
APPLICATION FILED AUG. 27, 1918.

1,302,399.

Patented Apr. 29, 1919.

UNITED STATES PATENT OFFICE.

JOHN F. MARTIN, OF GENTRY, ARKANSAS.

CANDLE-HOLDER.

1,302,399.

Specification of Letters Patent. Patented Apr. 29, 1919.

Application filed August 27, 1918. Serial No. 251,653.

To all whom it may concern:

Be it known that I, JOHN F. MARTIN, a citizen of the United States, residing at Gentry, in the county of Benton and State of Arkansas, have invented new and useful Improvements in Candle-Holders, of which the following is a specification.

This invention relates to candle holders, particularly to that type adapted for hand use, and has for its object the provision of a candle holder embodying a base having mounted thereon a candle support including a prong for engaging the base of the candle and resilient arms gripping the candle at a point considerably above the base whereby the candle will be held in a perfectly upright position and prevented from falling over, thereby eliminating the danger of fire caused by such falling over and preventing spilling of the melted grease upon carpets, furniture and clothing.

An important object is the provision of a candle holder of this character provided with a detachable auxiliary member adapted to be associated with the candle support proper whereby short ends or remnants of candles may be conveniently utilized and still maintained in an upright position.

A further object is the provision of a device of this character the base of which is provided with means for holding a plurality of matches in a position convenient to the user and also for holding the stems of the burnt matches.

An additional object is the provision of a candle holder of this character the base of which is provided with a scratching member whereby the matches may be conveniently ignited without the necessity of striking them upon walls or other places.

Another object is the provision of a device of this character which will be simple and inexpensive in manufacture, pleasing in appearance, efficient in use, durable in service and a general improvement of the art.

With the above and other objects and advantages in view, the invention consists in the details of construction to be hereinafter more fully described and claimed, and illustrated in the accompanying drawing, in which:—

Figure 1 is a plan view of the candle holder;

Fig. 2 is a front elevation thereof;

Fig. 3 is a longitudinal sectional view;

Fig. 4 is a similar view showing the remnant pan in position; and

Fig. 5 is a perspective detail view of the remnant pan detached.

Fig. 6 is a perspective detail view of the means for securing the candle holder to the plate.

Referring more particularly to the drawing the numeral 5 designates the base of my device which is formed preferably as a flat plate circular in form or of any desired angular configuration. Upon its underside, the base is preferably provided with a plurality of supporting feet 6 and upon its upper side adjacent one edge is provided with a handle 70 whereby it may be conveniently carried.

Extending upwardly at the center of the base 5 is a standard 8 which carries at its upper end a plate 9 provided with downwardly extending side flanges 10.

The candle holding portion of my device is formed preferably from a single sheet of resilient material which is bent intermediate its ends to provide downwardly extending portions 11 defining therebetween a base portion 12 having laterally extending lugs 13. The plate 9 has its upper surface recessed as shown for conforming engagement of the base portion 12 and lugs 13 of the candle holder. The lugs 13 are disposed 85 within cutaway portions 14 in the plate 9 at the flanges 10. The candle holder further comprises two arms 15 which extend from the base portion 12 and which are curved upwardly and toward each other and are provided at their meeting ends with arcuate jaws 16 which may be preferably provided with serrations 17 for more effectively gripping the candle to be held.

The base portion 12 of the candle holding member is held in secured relation upon the plate 9 by a plate 18 provided at one end with an upwardly extending finger engaging flange 19 and having its side edges provided with flanges 20 slidably engageable upon the flanges 10 of the plate 9. When the plate 18 is properly disposed upon the plate 9 it will confine the base 12 of the candle holding member in position upon the plate 9. At its center, the plate 18 carries an upstanding 100 prong or tine 21 adapted for penetrating engagement with the butt end of a candle. A candle to be held by my device has its butt end engaged upon the tine 21 and has its intermediate portion disposed between and 110

gripped by the jaws 16. On account of these jaws, the candle will consequently be held in an upright position and prevented from falling over.

5 In order to provide means whereby the short ends or remnants of candles may be utilized, I provide an auxiliary plate 21' which is provided at its sides with flanges 22 engageable upon the flanges 20 of the 10 plate 18 and provided at one end with an upwardly extending finger engaging flange 23. A bracket 24 is carried by the plate 21' and is offset therefrom as clearly shown and carries upon its upper surface a cup 25 within 15 which the short end or remnant of a candle may be placed. When it is desired to use a short end of a candle, it is merely necessary to engage the plate 21' upon the top of the plate 18 by engaging the flanges 22 upon 20 the flanges 20 and sliding the plate 21' along the plate 18 until the cup 25 is disposed immediately above the tine or prong 21. If desired, instead of engaging the plate 21' upon the plate 18, the plate 18 may be removed 25 and the candle holding member removed after which the plate 18 may be re-engaged upon the plate 9 and the plate 21' disposed upon the plate 18. This latter alternative arrangement would eliminate 30 the disadvantage of having the flame from a short end of a candle play upon the jaws 16.

In order to provide means whereby used and unused matches may be held conveniently upon the plate 9, I provide a pair of 35 wire members 26 and 27 which are formed as shown. The member 26 is adapted for the insertion of unused matches and will hold the matches in convenient position so that they may be readily grasped by the operator 40 when desired. After the matches have been struck and ignited, they may be inserted within the member 27 and held firmly therein.

Furthermore in order to still more greatly 45 increase the convenience of the device, I provide a scratching member 28 which may be formed of any desired construction and material and which is suitably connected with one of the members 26 or 27 as shown at 29.

50 In order that the device may be so constructed that the unused matches will be protected from tampering by children or be protected from injury by the weather, I may, if desired, provide a hinged cover for covering the member 26 within which the unused matches are disposed.

From the foregoing description and a 60 study of the drawing it will be apparent that I have thus provided a very simple and efficient device which will hold a candle firmly so that all danger of its falling over will be prevented and which is so constructed as to enable short ends or remnants of candles to be utilized instead of being thrown away as 65 is the common practice. Furthermore, it

will be observed that the device is very convenient as it provides in one body not only means for holding a candle but also means for holding used and unused matches and in addition a member upon which the matches 70 may be struck.

It will of course be readily understood that I reserve the right to make such changes in the form, and construction of arrangement of parts as will not depart from the spirit 75 of the invention or the scope of the subjoined claims, and it will be manifest that I may provide other means for securing the candle holding member upon the plate 9 and that the entire device may be made as ornamental 80 or artistic as desired.

Having thus described my invention I claim:

1. A device of the character described comprising a base, a standard rising therefrom, a plate mounted on said standard and provided with side flanges extending downwardly, a candle holding member mounted on said plate and including resilient arms curved to extend toward each other and terminating in clamping jaws, and a clamping plate slidably engaged upon said flanges and disposed over the base of the candle holding member.

2. A device of the character described comprising a base, a standard rising therefrom, a plate carried by said standard, and having side flanges, said plate having its upper surface recessed, a candle holding member formed from a strip of resilient material and including an intermediate base portion disposed within the recess in said plate, and further including resilient curved arms extending toward each other and terminating in clamping jaws spaced above 105 said plate, and a holding plate slidable upon said first named plate and provided with side flanges engageable beneath said first named flanges.

3. A device of the character described comprising a base, a standard rising therefrom, a plate carried by said standard and having side flanges, said plate having its upper surface recessed, a candle holding member formed from a strip of resilient material and including an intermediate base portion disposed within the recess in said plate, and further including resilient curved arms extending toward each other and terminating in clamping jaws spaced above 110 said plate, and a holding plate slidable upon said first named plate and provided with side flanges engageable beneath said first named flanges, and an auxiliary plate disposed upon said last named plate and slidably engageable thereon, and a cup carried by said last named plate.

4. A device of the character described comprising a base, a standard rising therefrom, a plate mounted on the upper end of 130

said standard and provided with depending side flanges and having its upper surface recessed, a candle holding member mounted on said plate and having its intermediate portion bent to provide depending portions, said depending portions defining therebetween a base portion disposed within said recess, said candle holding member further including resilient arms curved to extend toward each other and terminating in 10 clamping jaws, and a plate detachably engageable upon said first named plate and provided with depending flanges engaging with said first named flanges, said last named plate confining the base of said candle holding member within said recess. 15

In testimony whereof I affix my signature.
JOHN F. MARTIN.
